UNITED STATES PATENT OFFICE

165,419

TWIN-WHEEL TOOL GRINDER

John J. Falls, Cincinnati, Ohio, assignor to The Standard Electrical Tool Company, Cincinnati, Ohio, a corporation of Ohio

Application April 6, 1951, Serial No. 14,735

Term of patent 14 years

(Cl. D37—1)

To all whom it may concern:

Be it known that I, John J. Falls, a citizen of the United States of America, residing at Cincinnati, in the county of Hamilton, Ohio, have invented a new, original, and ornamental Design for a Twin-Wheel Tool Grinder, of which the following is a specification, reference being had to the accompanying drawing, forming a part hereof.

The drawing figure is a perspective view of the twin-wheel tool grinder of the invention, showing the front and one side thereof, the opposite side being identical to the side shown, and the rear being a plain panel having no design characteristics.

I claim:

The ornamental design for a twin-wheel tool grinder, as shown and described.

JOHN J. FALLS.
